UNITED STATES PATENT OFFICE

2,006,505

TANK ROOF

Boris Lentschewsky, Berlin, Germany

Application March 14, 1932, Serial No. 598,851
In Germany March 24, 1931

8 Claims. (Cl. 220—26)

The invention relates to a semi-rigid insulating roof or top for protecting liquid fuels against fire or evaporation.

It is known to construct roofs of this nature from single fields, or also a plurality thereof. The known arrangements, however, are either relatively complicated in construction, or fail to seal off the surface of the liquid in tight fashion at all points.

It is the primary object of this invention to overcome the disadvantages in question, and this is accomplished by the fact that the adjacent edges of a series of fields form overlapping portions, and at the corners there are provided flat tongues, which at the same time serve to perform sealing against the neighbouring and the succeeding series. Each floating field may be constructed in step-like fashion, in order in this manner to obtain connection between the adjacent fields. This connection, however, may also be performed by means of grooves and tongues.

The arrangement according to the invention is accompanied by the additional advantage that even considerable deformation of the tank or improper form thereof will have no detrimental effect on the insulating properties of the roof.

Other objects and advantages of the invention will become apparent as the description proceeds.

The invention will now be described more fully with reference to the accompanying drawings, in which

Fig. 1 shows an insulating roof, constructed according to the invention, for a cylindrical tank.

Fig. 2 shows a single floating field in plan.

Fig. 3 is a section of the field according to Fig. 2 along the line III—III.

Figs. 4, 5 and 6 are additional embodiments of the floating field in cross-section.

Fig. 7 shows on enlarged scale a part elevational view of the field connection.

Fig. 8, on similar scale, shows the connection of modified forms of field.

Fig. 9 illustrates an additional method of connecting the fields.

Fig. 10 shows a modified form of assembly of the roof.

Figs. 11, 12 and 13 show different embodiments of the seal between the roof and the wall of the tank.

Fig. 14 shows an additional embodiment of the insulating roof according to the invention, in plan.

Fig. 15 illustrates the roof according to Fig. 14 in cross-section.

Figs. 16 and 17 show a detail of the arrangement in elevation and in plan.

The insulating roof according to Fig. 1 consists of single rectangular fields 1 adjoined by supplementary fields 2 for the purpose of providing the roof with a circular form. The single floating fields 1 in the embodiment according to Figs. 2 and 3 consist of two flat boxes or cells 3, which are disposed in staggered relation to each other diagonally, and may be connected together in any suitable or desired manner. Between the cells 3 there is located a sheet or plate composed of asbestos, metal or the like, which supplements or fills out the free corners resulting from the staggered disposal of the cells, as shown in Figs. 2 and 3, in which these are shown as tongues 33. The staggered disposal of the flat cells results in the formation of steps 5.

The construction of the floating field 1 may also be such that the steps 5 are secured in suitable fashion to the edges of one single floating cell 6 of corresponding height, these steps being constructed as separate elements 7 (Fig. 4).

To increase the insulating powers of the roof the single fields 1 may also be composed of more than two, for example three, flat cells 3 (Fig. 5), so that fields are formed having three or more steps and engaging with each other by the horizontal faces of the steps. In accordance with Fig. 6, the three or more single flat cells 3 are connected in staggered relation to each other in such fashion that the adjacent fields 1 interengage at their edge portions in the manner of tongue and groove. Obviously, however, the embodiments according to Figs. 5 and 6 may also make use of the arrangement according to Fig. 4.

In order to ensure that the peripheral edge of the roof rests as tightly as possible against the inner wall of the tank 8, means are provided according to the invention, which have the tendency to force the single fields 1 and 2 apart within certain limits. In the form of embodiment according to the drawings spring arrangements are employed, which in their particular construction are shown more particularly by Figs. 7, 8 and 9. In the embodiment according to Figs. 7 and 8 bearing brackets 9 are provided towards the edge of the single fields 1, and in these brackets there are mounted, preferably vertically to the corresponding edges of the fields 1, bolts 10 which are capable of longitudinal displacement. The distance between the head 11 and the nut 12 of the bolt 10 is so calculated that when the bracket 9 is in contact with either of these parts the engage-

ment between the steps 5 is sufficient to form a proper seal.

On the bolt 10 there is placed a coil spring acting as pressure spring 13, which thrusts with its 5 ends against the oppositely situated brackets 9, and thus seeks to force the fields 1 apart. In the embodiment according to Fig. 9 there is provided a flat spring 14 acting as pressure spring, which is held at its centre on the one field 1 by a bracket 10 15, the ends thereof sliding in brackets 16 on the adjacent field 1. To prevent lifting of the horizontal faces of the steps 5 it is desirable to provide on the underside of the fields 1 an additional guide 17, which together with the guide for the 15 spring 13 secures the roof against separate vertical movements on the part of the single fields 1, and thus forms a structure of a semi-rigid kind. In the embodiment according to Fig. 9 there is in itself a certain security against undesirable vertical movement on the part of the single fields by reason of the edgewise disposal of the spring 14, and if necessary this may also be supplemented by the arrangement 17.

The roof according to Fig. 10 consists of one 25 large middle field 18, which is surrounded by an annular structure of sector fields 19. The single fields 19 are constructed in similar fashion to the fields 1. In this case spring arrangements according to Figs. 7, 8 and 9 are also provided for regulating the periphery in accordance with contraction or expansion on the part of the tank.

It will be obvious that in lieu of the spring devices as shown it is also possible to employ other means for fulfilling the object according to the 35 invention. Thus, for example, there might also be provided a poise-weight or counter-weight device engaging in corresponding fashion with the fields 1, 2, 18 or 19.

In the embodiment according to Fig. 10 there 40 may if necessary also be provided an additional sector-ring 19. Obviously in place of the large circular centre field 18 there may be employed a correspondingly smaller field, between which and the sector ring 19 there is inserted an additional 45 ring constructed on similar lines. In an embodiment of the roof according to Fig. 10 the arrangement of the steps 5 at the central field 18 will preferably be such that the upper steps, for example, of the central field 18 rest on the lower 50 steps of the sector-fields 19. A possible embodiment of this kind is revealed in section by Fig. 8.

To ensure that the horizontal faces of the steps fit tightly against each other the buoyancy of adjacent fields is, according to the invention, made 55 to vary. Difference in the buoyancy may be regulated by means of weights.

Peripheral sealing of the roof may be performed in accordance with Figs. 11-13 either by the provision of labyrinth recesses 20 in the peripheral walls of the fields 2 or sectors 19 or, assuming the tank is composed of plates secured by rivets, by the provision of metallic wire brushes 21 acting in sealing fashion, or alternatively by providing elastic packing members 22, springs or the like between the wall of the tank 8 and the peripheral wall of the roof.

Fig. 14 shows a modified form of embodiment of the roof according to the invention. Figs. 14 and 15 illustrate three variations of the same embodiment. In this case the roof consists of rectangular fields 23 and correspondingly constructed supplementary fields 24. These single fields are also constructed in step-like fashion at the edges, but in contradistinction to the embodiments previously described all of the steps are situated in

the one direction, that is to say—the lower steps in the initial position are all situated close together, whilst the upper steps recede in relation to the first ones.

In the variation illustrated on the left hand side of Figs. 14 and 15 the upper edges of the upper steps are connected with each other by means of double hinge members 25, which take the part of the connection roof providing a complete seal. In particular, the variation shown at the extreme left of Figs. 14 and 15 is primarily intended for use in connection with insulating roofs for liquid fuels of high specific weight, as relatively few volatile constituents are separated from fuels of this nature. The hinge members 15 consist of a plurality of longitudinal sections, the ends of which overlap.

In the variation shown in the middle portion of Fig. 15 there is also provided, in addition to the hinge device 25 above referred to, a metal tape 20 or band 26 situated on the horizontal faces of the lowermost steps. This tape 26 possesses a width, which is equal to the total width of the oppositely located horizontal step faces, and consists of a plurality of parts connected longitudinally, the ends of which slide one upon the other. The tape 26 is furnished with bolts 27 provided in the slots 28 of guide arms 29, which are preferably secured in direct fashion to the fields 23, 24 at a distance from the horizontal faces of the 30 steps corresponding with the thickness of the tape 26.

This embodiment also ensures an excellent sealing of the joints of the roof. As shown on the right hand side of Figs. 14 and 15, the metal 35 tape 26 may also be provided without the hinge members 25. A particularly tight guiding of the tape 26 may be accomplished by the provision of pressure springs 32 between the nuts 30 and the washers 31 of the bolts 27 (Figs. 16 and 17).

The height of the lowermost steps on the edge faces of the single fields is dependent on the quantity of liquid displaced and the nature of the same, and is preferably so chosen that the horizontal faces of the lowermost steps are situated above the level of the liquid. If necessary, therefore, the lowermost steps may be constructed considerably higher than the others. On the other hand the height of the lowermost steps must, in accordance with the specific weight of 45 the liquid fuel, be so chosen that the layer of air between the surface of the liquid and the horizontal step faces situated next to the same and engaging with each other is as small as possible, so that losses by evaporation will be reduced to 50 a minimum.

The invention furthermore provides for construction of the single fields for the reception of fire-extinguishing means, such as CO₂, foam-forming substances or the like. The construction 60 may either be such that the fields themselves act as containers for the fire-extinguishing agent, or that separate containers may be secured to the upper or lower sides. In this form of construction of the fields the latter required to possess a 65 buoyancy which is such that the same, despite the load imposed thereon, are situated with the lowermost horizontal faces of the stepped edges above the level of the liquid.

The fields are furnished in their faces and 70 preferably also along their edges with apertures, which are sealed by means of metal plugs 4 capable of fusing at a certain predetermined temperature, thus permitting of regulation of the density of the air in the box-like field, and also, 75

if the fields are constructed as receptacles or containers for a fire-extinguishing agent, of the exit of this agent between the slots and on the upper side of the roof.

5 A similar arrangement may also be provided if separate receptacles for the fire-extinguishing agent are mounted on the fields. In place of the readily fusing metal plugs employed to close the outlet apertures there may also be used mechanically movable closing means, which are controlled by one or more thermostats adjusted to a certain pre-determined temperature.

10 If the single fields, as already described in the above, consist of two or more superimposed flat boxes in staggered relation to each other, there may be provided, for the purpose of increased insulation on the part of the fields, more particularly against external heat, a sheet of asbestos or similar insulating material between each two 15 adjacent boxes. This intermediate layer preferably also covers the horizontal faces of the steps at the edges, and thus at the same time ensures increased sealing efficiency on the part of the contacting horizontal faces of the steps of adjacent fields.

20 In all of the embodiments referred to the cells or boxes forming the fields may be filled out wholly or in part with light insulating materials, such for example as cork or the like, insofar as 25 the same are not required for the reception of fire-extinguishing agents. In the latter case the extinguishing agent will conveniently be furnished in the lowermost box or cell, whilst the remaining cells or boxes are filled with a light 30 insulating material, or alternately with such material and with the extinguishing agent.

35 It will be understood that no restriction is made to the specific forms of embodiment shown, which have been quoted solely by way of example, and 40 that various modifications are quite possible within the meaning of the above description and the annexed claims without departing from the spirit of the invention.

45 What I claim as new and desire to secure by Letters Patent is:

1. In an insulating roof for tanks for liquid fuels, a plurality of floating cells so assembled as to correspond with the peripheral form of the tank, projectory portions on the said cells forming stepped edges, the stepped edges of each cell being 50 adapted to fit into the stepped edges of adjacent cells to provide a substantially flat surfaced roof, means for connecting the individual cells together and means for sealing the roof about the periphery.

55 2. In an insulating roof for tanks for liquid fuels, etc., a plurality of floating cells so assembled as to correspond with the peripheral form of the tank, projectory portions on the said cells forming stepped edges, the stepped edges of each cell being adapted to fit into the stepped edges of adjacent cells to provide a substantially flat surfaced roof, flat tongues at the corners of the said 60 cells, means for connecting the single cells to-

gether, and means for sealing the roof about the periphery.

3. In an insulating roof for tanks for liquid fuels, etc., a plurality of floating cells so assembled as to correspond with the peripheral form of the tank, projectory portions on the said cells forming stepped edges, the stepped edges of each cell being adapted to fit into the stepped edges of adjacent cells to provide a substantially flat surfaced roof, flat portions overlapping the joints formed by projectory portions between adjacent cells, resilient means for connecting the said cells together, and means for sealing the roof about the periphery.

10 4. In an insulating roof for tanks for liquid fuels, etc., a plurality of floating cells so assembled as to correspond with the peripheral form of the tank and adapted to contain a fire-extinguishing agent, plugs in the said cells adapted to fuse at a certain temperature, step-like structures at the 15 edges of the said cells adapted to overlap with corresponding structures on the adjacent cells, means for connecting the cells together, and means for sealing the roof about the periphery.

20 5. In a form of embodiment of an insulating roof for tanks for liquid fuels, etc., a plurality of floating cells so assembled as to correspond with the peripheral form of the tank and composed of a plurality of flat, superimposed boxlike structures disposed in staggered relation to each other 25 to form steps at the edges of the said cells adapted to overlap with correspondingly formed steps on the adjacent cells, flat tongues at the corners of the said cells, a fire-extinguishing agent in association with the said cells, plugs adapted to 30 fuse at a certain temperature to permit of discharge of the said fire-extinguishing agent, springs mounted on each two adjacent cells adapted to force the said cells outwardly to a limited extent to fit tightly against the wall of the 35 said tank, and means for preventing vertical lifting on the part of single cells.

40 6. In a form of embodiment of an insulating roof for tanks for liquid fuels, etc., according to claim 5, means for sealing the said roof about the 45 periphery.

7. In a form of embodiment of an insulating roof for tanks for liquid fuels, etc., according to claim 5, means for imparting varying buoyancy to the said cells.

50 8. In an insulating roof for tanks for liquid fuels, a plurality of floating cells so assembled as to correspond with the peripheral form of the tank, outwardly extending portions on the said cells adapted to form projecting and re-entrant portions on the sides of the cells, the projecting and re-entrant portions of the cells adapted to fit respectively the re-entrant and projecting portions of adjacent cells to provide a substantially flat surfaced roof, means for connecting the single 55 cells together and means for sealing the roof about the periphery.

60 BORIS LENTSCHEWSKY.
